UNITED STATES PATENT OFFICE

WILLIAM EPPS ROBERTSON, OF RICHMOND, VIRGINIA

FIRE ESCAPE

Application filed October 16, 1929. Serial No. 490,006.

This invention appertains to new and useful improvements in fire escapes and more particularly to a novel chute of the collapsible type.

The principal object of this invention is to provide a life saving chute which can be quickly mounted for use without difficulty.

Another important object of the invention is to provide a fire escape in the form of a chute attachment for ladders.

During the course of the following specification and claims, other important objects and advantages of the invention will readily become apparent.

In the drawings:

Figure 1 represents a side elevation of an extension ladder mounted on a fire apparatus with the novel attachment arranged thereon.

Figure 2 represents a cross sectional view through the especially equipped ladder.

Figure 3 represents a cross sectional view of the novel belt structure.

Figure 4 represents a front elevational view of the extension ladder and the belt arranged longitudinally thereon.

Figure 5 represents an end elevation of the ladder with the attachment disposed in place thereon.

Figure 6 represents a fragmentary longitudinal sectional view through the ladder and the attachment thereon.

Figure 7 represents a top plan view of a ladder section with the chute attachment arranged thereon.

Figure 8 represents a longitudinal sectional view through the belt.

Figure 9 represents a fragmentary perspective view of the belt.

Figure 10 represents a longitudinal sectional view through a slightly modified form of the invention.

Figure 11 represents a fragmentary elevational view of the modification shown in Figure 10.

Figure 12 represents a side elevational view of the winding means for the belt.

Figure 13 represents a cross sectional view taken substantially on line 13—13 of Figure 12.

Figure 14 represents a fragmentary side

elevational view of the modification shown in Figure 10.

Referring to the drawings wherein like numerals designate like parts, it can be seen that Figures 1, 2, 4, 5, 6 and 7 disclose the invention in the form of an attachment for bar apparatus ladders. In Figure 1, the platform 5 of a piece of fire apparatus has the upright 6 thereon for swingably supporting the extension ladder generally referred to by numeral 7.

As shown in Figure 5, this ladder comprises a pair of sections each including a pair of side rails 8, 8 connected by the rungs 9.

In carrying out the present invention, each side rail 8 has an elongated flange 10 secured thereto and these flanges are braced by the reinforcing straps 11. The outer longitudinal edge portion of the flanges 10 are curved outwardly as at 12. This eliminates a sharp edge so that the hands of persons sliding down the chute will not be cut. It will be noted that the flanges 10 of the slideable sections of the ladder will overlap so that the sections of the ladder may be disposed in contracted position when the ladder is not in use.

The ladder is partly shown in contracted position in Figure 1. As is clearly shown in Figure 7, as well as other views of the drawings, the belt comprises a plurality of plates 13, connected in abutting relation by means of a plurality of flexible straps 14. Suitable rivets 15 may be employed for securing the said plates to the straps. The straps 14 at one end are secured to one end of the ladder preferably in the manner shown in the modified form. (See Figure 10.)

The opposite end of each strap is connected to a split roll 16, which roll is clearly shown in Figures 12 and 13 and is also employed in the modified form shown in Figure 10. This roll has a plurality of nuts 17 fixed therein and eyebolts 18 have their threaded shanks engaged in the said nuts 17 in a manner so that the eyes thereof will protrude beyond the outer surface of the roll, and as shown in Figure 13, the roll is recessed as at 19 around each eye so that it will not be necessary for the eyes to protrude beyond the periphery of the roll.

5 The ends of the strap 14 which are secured to the roll 16 are provided with eye members 20 for connection to the said eyes 18 in the manner clearly shown in Figure 6, or in the modified form 10 which is identical. It
will also be observed in Figure 6, that the straps 14 are trained over the rods 21 which connects the side rails 8-8 of the ladder.

10 A pawl 22 and ratchet 23 are also associated with the roll 16 for retaining the roll against unwinding and a removable crank 24 may be employed for rotating the roll.

15 In Figure 10, a modification is shown which involves a pair of sections generally referred to by numerals 25-25. Each of these sections includes a pair of side bars 26-26 to which the flange plates 27 are secured and braced by the reinforcing straps 28. These flange plates 27 are also curved outwardly at 20 their outer longitudinal edges as denoted by numeral 29.

25 As is clearly shown in Figure 10, the side bars 26-26 have their inner ends pivotally connected together at one longitudinal edge as at 30, while apertured ears or eyelets 31 are provided along the opposite or longitudinal edge adjacent their abutting ends to receive the pin 32 which pin serves to secure the sections 25-25 in a rigid lined position.

30 For supporting the belt hereinbefore described, a plurality of rungs 33 connect the side bars 26-26 and at one end of this modified structure a rung 34 is provided for engagement by the snap hooks 35 at one end 35 of each strap 14. The ends of the straps at the other end of the modified structure are secured to the roll 16 in the manner consistent with the description herein relative to the ladder attachment.

40 Furthermore, the same pawl and ratchet means is provided as well as the crank for actuating the roll 16.

45 While the foregoing description sets forth the invention in detail, it is to be understood that numerous changes in the shape, size and materials may be resorted to without departing from the spirit and scope of the invention as claimed hereinafter.

Having described the invention, what is 50 claimed as new is:

1. A fire escape of the class described comprising a ladder, upstanding longitudinally extending members connected to the side rails of the ladder, and having their upper edges 55 curved outwardly, a flexible member passing over the rungs of the ladder and having its ends connected with the ends of the ladder and plates connected to the flexible member and having their edges contacting each other, 60 said plates forming a bottom of a chute, the sides of which are formed by the flanges.

65 2. A fire escape of the class described comprising an extensible ladder, upstanding longitudinally extending flanges connected with the side rails of the ladder and having their

upper edges curved outwardly, a flexible member extending over the rungs of the ladder, plates connected with the flexible member and forming a bottom of a chute, the side walls of which are formed by the flanges with means for connecting one end of the flexible member to one end of the ladder and a roller supported by the other end of the ladder and to which the other end of the flexible member is connected.

70 75 In testimony whereof I affix my signature.
WILLIAM EPPS ROBERTSON.
